FILTER

Frank A. Headson, Milwaukee, Wis.

Original application October 18, 1933, Serial No. 694,047. Divided and this application April 29, 1935, Serial No. 18,843

7 Claims. (Cl. 210—169)

The invention relates to filters suitable for oil reclaiming and other uses, and has for an object to provide an effective filter capable of relatively free passage of liquid therethrough and permitting normal operation without need for placing the liquid under pressure.

Another object of the invention is to provide a simple and durable means for cleaning the surface of a filter pad and for facilitating the entrance of the liquid into the pad.

The invention further consists in the several features hereinafter described and claimed.

One specific embodiment of the invention is illustrated in the accompanying drawing, where-
15 in

Fig. 1 is a vertical sectional view of a filter constructed in accordance with the invention;

Fig. 2 is a sectional view taken on the line 2—2 of Fig. 1;

20 Fig. 3 is a sectional view taken on the line 3—3 of Fig. 1, and

Fig. 4 is a perspective view of one of the filter pad scrapers.

In the drawing, 25 designates a suitable housing within which is secured a horizontal receptacle-forming bracket or frame 114. A horizontal shaft 115 is journaled in the bracket and is driven by any suitable source of power such as an electric motor, not shown, through a flexible coupling 111. The shaft 115 carries a worm 118 which meshes with a worm wheel 119 carried on a vertical shaft 120 journaled in the bracket 114 and in a bearing plate 121 secured above the bracket. The vertical shaft 120 carries a pinion 122 which meshes with a gear 123 on a vertical shaft 124 journaled in the bracket and bearing plate. Below the bracket the shaft 124 has a downwardly projecting squared portion on which is slidably mounted against relative rotation a trough-forming arm 125 (Figs. 1 and 3) having an enlarged central portion which registers with an oil drain opening 126 in the bracket or frame.

Oil is admitted to the receptacle-forming bracket 114 in any suitable manner, as from the drain pipe or nozzle 91 of a still, not shown. The oil draining from the pipe 91 lubricates the gearing on the bracket and drains through the opening 126 into the rotary trough-forming arm 125 which turns at a slow speed. The arm 125 is divided into two basins by an angular transverse rib 125' at its hub portion, and the downward movement of the arm is limited by a pin 127 on the shaft 124. Drain openings 128 are formed 55 near opposite ends of the arm at different radii

from the shaft 124, and the longer end of the arm receives more oil than the shorter end.

Oil drops from the rotary arm 125 onto a cushion-like filter pad 129 which preferably consists of a ribbon of cellulose cotton having a crepe surface and wound into a resilient, compressible, spongy, cylindrical block or disk about a cardboard core 129', the axis of the block extending vertically. The pad is supported in a cup-shaped holder 130 and rests on radial ribs 131 formed on the bottom wall of the holder. The bottom wall of the holder is conical and converges downwardly to a central drain opening 132. The core 129' of the pad has fitted therein a sediment cup 133 to receive foreign matter. The cup rests on the notched inner ends of the ribs 131 and the top surface of the pad slopes downwardly to the upper edge of the cup which is marginally flanged.

The bottom wall of the pad holder has downwardly projecting bosses 134 to which a pair of spaced parallel horizontal bars 135 are secured by screws 136. The bars are slidably guided in tracks 137 mounted on the top wall of a tank 138 below the pad holder, so that the holder may be removed from the housing to replace the pad. The top wall of the tank 138 has an opening 140 registering with the drain opening 132 in the pad holder 130 to receive the filtered oil, which is ready for use and is drawn from the tank at suitable intervals.

The upper surface of the filter pad 129 tends to become coated with a deposit which prevents free passage of the oil. This deposit is removed by a plurality of scraper shoes 141 and 142 which slidably bear on the upper surface of the pad, and are impelled by the rotary arm 125. The arm 125 carries a pair of parallel horizontal transversely extending pins 143 at opposite sides of its axis. Each pin pivotally carries a bell-crank 144 on the lower ends of which are pins 145. An L-shaped connector 146 is pivotally mounted on each pin and has a depending leg carrying a cross pin 147. Each scraper shoe is notched at its rear edge to receive the depending connector leg and is pivoted thereon by the cross pin 147. At one side edge the scraper shoe is provided with spaced upstanding jaws 148 loosely receiving between them the laterally projecting leg of the connector 146 to limit the swinging movement of the scraper. On each scraper shoe 141 (Fig. 4) the jaws 148 are at one side edge, while on each scraper shoe 142 the jaws are at the other side edge. Each scraper shoe has a diagonal upstanding flange 55

149 which works foreign matter toward the central sediment cup 133. The bottom of each scraper shoe is arched, as seen in Fig. 4, and each has a front scraping edge and a rounded rear heel 150 which rest on the pad, the weight being so distributed as to avoid excessive pressure on the pad at the scraping edge. The scraper shoes also have the effect of pressing the filter pad, the resilience of which restores it to normal shape in condition to readily absorb oil. The compression and recovery of the resilient filter pad urges the oil through the pad, the action occurring being somewhat in the nature of a pumping action.

In operation, oil drops onto the receptacle-forming bracket or frame 114 where it lubricates the gearing for the pad cleaner before being discharged by gravity through the opening 126 and onto the rotary trough-forming arm 125. From the arm 125 the oil is distributed through the drain openings 128 onto the upper surface of the filter pad 129 in the paths of the scraper shoes and seeps through the pad. The scraper shoes 141 and 142 scrape the deposit from the upper surface of the pad, the deposit finding its way into the central sediment cup 133. The scrapers also press the resilient pad in their travel, locally depressing the surface of the pad. In each pass of a scraper shoe, the scraping edge thereof effects one compression of the filter pad, and the heel thereof effects a second compression of the pad. The filter removes paraffin and asphaltic material from the oil. The oil flows through the filter pad parallel to the plies and the foreign matter is deposited mainly between the plies. The filtered oil is drained from the opening 132 in the pad holder and enters the finished oil tank 138 from which it is drawn for use.

The filter pad requires periodic renewal, the holder 130 being preferably removed from the housing for this purpose. When removing the holder, the rotary arm is slid up on the shaft 124, as indicated by dotted lines in Fig. 1. The sediment cup 133 is removed from the discarded pad and placed in the new pad.

This application constitutes a division of my application for Oil reclaimers, Serial No. 694,047, filed October 18, 1933.

What I claim as new and desire to secure by Letters Patent is:

1. The combination of a cushion-like filter pad of resilient, compressible, spongy material for receiving liquid thereon, and a pad-pressing and

scraping shoe relatively movable along the surface of the pad for facilitating the absorption of liquid by the pad through the compression and recovery of the pad, said compression and recovery of the pad causing a pumping action on the liquid entering the pad.

2. The combination of a resilient filter pad for receiving liquid thereon, and a relatively movable pad-engaging scraper shoe supported by said pad for cleaning the surface of the pad, said scraper having a forwardly projecting scraping edge bearing on the pad.

3. The combination of a resilient filter pad for receiving liquid on its upper surface, and a relatively movable shoe bearing on said surface and supported by said surface, said shoe having a leading pad-engaging scraping edge and a trailing pad-engaging heel and having an elevated bottom between said scraping edge and heel.

4. In combination, a cushion-like filter pad of resilient, compressible, spongy material, and pad-pressing and scraping means relatively movable along the surface of said pad for facilitating the absorption of liquid by the pad through the compression and recovery of the pad, said compression and recovery of the pad effecting a pumping action on the liquid.

5. In combination, a filter element, a shoe relatively movable with respect to said filter element and bearing on said filter element, and means for pressing said shoe against said filter element and having a pivotal connection with said shoe to substantially equalize the bearing of opposite sides of said shoe on said filter element, the axis of said pivotal connection extending substantially in the direction of movement and at an intermediate portion of said shoe.

6. The combination of a filter element for receiving liquid on its upper surface, a member rotatable above said element about a substantially vertical axis, means for rotating said member, an equalizing lever pivotally secured to said rotatable member, and shoes pivotally connected to said equalizing lever and movable on said surface.

7. In combination, a filter pad, an impelling member above said pad rotatable about a substantially vertical axis and forming a liquid-carrying distributor, and a pad-pressing scraper relatively impelled by said member along the surface of said pad, said rotatable member having an outlet for discharging liquid onto said pad in the path of said scraper.

FRANK A. HEADSON.
